(57) CLAIM

An ornamental design for packaging for an edible product, as shown and described.

DESCRIPTION

FIG. 1 is a front elevation view of packaging for an edible product;

FIG. 2 is a front plan view of packaging for an edible product shown in FIG. 1;

FIG. 3 is a rear plan view of packaging for an edible product shown in FIG. 1;

FIG. 4 is a side view of packaging for an edible product shown in FIG. 1;

FIG. 5 is the opposing side of the view of packaging for an edible product shown in FIG. 4;

FIG. 6 is a top view of packaging for an edible product shown in FIG. 1; and,

FIG. 7 is a bottom view of packaging for an edible product shown in FIG. 1.

The broken lines representing a candy cane, bow and interior pouch are for illustrative purposes only and form no part of the claimed design.

It is understood that the claimed design is shown as a solid line disclosure, including the transparent wrapping covering the candy cane.
